DESIGN FOR A PARLOR-STOVE.

SPECIFICATION forming part of Design No. 14,008, dated June 26, 1883.

Application filed April 14, 1883. Term of patent 3½ years.

UNITED STATES PATENT OFFICE.

FRANCIS KERNAN, JR., OF UTICA, NEW YORK, ASSIGNOR TO RUSSELL WHEELER, SON & CO., OF SAME PLACE.

DESIGN FOR A PARLOR-STOVE.

SPECIFICATION forming part of Design No. 14,008, dated June 26, 1883.

Application filed April 14, 1883. Term of patent 3½ years.

To all whom it may concern:

Be it known that I, FRANCIS KERNAN, Jr., a citizen of the United States, residing at Utica, in the county of Oneida and State of New York, have invented and produced a new and original ornamental Design for Parlor-Stoves, of which the following is a specification, reference being had to the accompanying photograph or illustration of a stove, which embodies my said new design.

The design for the top A, which has a rounded form and is surmounted by a vase, a, consists of the clover-shaped scroll ornament a', extending over almost the entire surface of said top, with one point thereof at both front and rear, and one at each side of said top, and having the scroll ornament a' pendent from each of said points, the smaller clover-shaped ornamentation b having one of its points in each of the spaces between the points of said ornament a', with the scroll ornament b' pendent from each of said points; the round scroll corner ornaments c, one located at each corner of said top, with the scroll ornaments c' pendent therefrom, and the spiral-shaped scroll ornament c', extending around said top, all shaped and arranged together so as to present the appearance represented in the accompanying photograph.

The design for the section B is composed of the front plate, D, which is somewhat bulging, and has rounded edges, which are provided with the row of dagger-shaped ornaments d, extending all around the same, the tablet e, fixed to the surface of said plate and extending diagonally across the same, with the raised letters e' thereon. Above said tablet is the compound triangular-shaped scroll ornamentation f, and below said tablet and occupying the entire remaining surface of said front plate is the compound triangular-shaped scroll ornamentation f'. Below said front plate, and resting on the shelf E, is an ornamented fender, F, extending the entire width of the stove, all shaped and located substantially as shown in the accompanying photograph.

The design for the fire-chamber section G consists of the door H, containing the four damper-openings g, with the compound flower-shaped scroll ornaments g' on the surface of

said door, at the sides of and between said openings, the three illuminating openings above said damper-openings, and the four compound scroll ornaments i, located on the surface of said door, at the sides of and between said openings. Upon the surface of the stove and at each side of said door are the compound vine-shaped scroll ornaments j, all shaped and arranged together as shown in the accompanying photograph.

The design for the extended base I consists of the round scroll ornaments k, one located over each of the front legs of the stove, the scroll ornaments k', extending from said k to the rear of said base, the compound scroll ornament k', and the two ornamented fenders, one being located at each extremity and ward the front of said base, all arranged as shown in the accompanying photograph.

The design for the feed-door side is composed of the door K, which has the row of dagger-shaped ornaments m at the top there the series of scroll ornaments m', the scroll ornaments m', the series of scroll ornaments extending diagonally across said door, and the compound scroll ornaments n', located above and the other below said series n; the upper part, L, which has the arrow-shaped ornamentation o, the compound scroll ornament o', and the figures o'; and the lower part M, which has the raised plate p, with the raised letters p' thereon, and the row of dagger-shaped ornaments q, all shaped and arranged as shown in the accompanying photograph.

The design for the legs consists, essential of the band-like top N, with the scroll ornament r thereon, the bulging pear-shaped portion O, with the compound scroll ornament s thereon, and the narrow base Q, with the scroll ornament t thereon, all shaped and arranged as shown in the accompanying photograph.

What I claim as my invention is—

1. The design for the top A, having the vase a and ornamentations a' a' b b' c c' c', combined and arranged as shown.
2. The design for the section B, composed of the front plate, D, having the diagonal tablet e, with letters e' thereon, and ornamentations d,

- e shelf E, and ornamented fender F, all arranged as shown.
3. The design for the fire-chamber section G, composed of the door H, having the parts $g' g''$, and the ornaments j , all combined and arranged together as shown.
4. The design for the extended base I, having the ornamentations $k' k''$ and fenders l , all aped and arranged as shown.
5. The design for the side, composed of the end-door K, having the ornamentations $m' m''$, $n' n''$, the section L, having ornamentations $o' o''$, and the section M, having the plate p and ornaments q , as described and shown.
6. The design for the legs, having the parts 15 N, O, and Q, with ornamentations r , s , and t , arranged and formed as shown.

In witness whereof I have hereunto set my hand in the presence of two witnesses.

FRANCIS KERNAN, JR.
